UNITED STATES PATENT OFFICE.

JAMES F. McLAUGHLIN, OF PHILADELPHIA, PENNSYLVANIA.

COMMUTATOR-BRUSH.

SPECIFICATION forming part of Letters Patent No. 432,206, dated July 15, 1890.

Application filed March 19, 1890. Serial No. 344,545. (No model.)

To all whom it may concern:

Be it known that I, JAMES F. McLAUGHLIN, a citizen of the United States, and a resident of Philadelphia, in the county of Philadelphia, and State of Pennsylvania, have invented certain new and useful Improvements in Commutator-Brushes, of which the following is a specification.

My invention has reference to improvements in collector-brushes for dynamo-electric generators and motors, the object being to render carbon brushes, which are now generally employed in dynamo-electric machines, more durable without impairing the general utility of such-brushes.

It has been found that if the collector-brushes for dynamo-electric machines are made of carbon the sparking heretofore observed when metallic brushes were used is almost entirely avoided, owing to the perfect contact which a body of carbon is capable of making with a moving surface. Collector-brushes of this character, however, have this disadvantage, that by reason of the lack of homogeneity of the carbon and by reason of the brittleness of the same the edges of the contact-surfaces are frequently broken away, whereby the extent of contact-surface is reduced and the brush is consumed much more rapidly than would otherwise be the case. It also frequently occurs that a carbon brush breaks away altogether between its contact-face and the brush-holder, and frequent renewals of new collector-brushes are therefore necessary. To obviate in a measure this last-mentioned defect, it has been found necessary to reduce the distance between the brush-holder and the face of the commutator to a minimum, for the longer the collector-brush is the greater is the liability of its being broken if made of such brittle substance as carbon. By my improvement I overcome all these objections in a very simple manner, as will appear from the following detailed description, in which reference is made to the accompanying drawings, which form a part thereof, and in which—

Figure 1 represents a perspective view of the commutator of a dynamo-electric machine provided with a collector-brush of my improved construction. Fig. 2 is a sectional view of my improved collector-brush with the

brush-holder and adjusting devices for the same, the section being taken on line *x x*, Fig. 1. Fig. 3 is an end view of the brush-holder with a pivoted frame supporting the feeding mechanism swung open; and Fig. 4 is a sectional view on the line *y y*, Fig. 3, with the feeding mechanism in position.

Like numerals of reference indicate like parts all throughout the drawings.

The commutator-cylinder 1, which may be of any ordinary or improved construction, has, as shown in the drawings, pivoted concentric with its axis an arm 2, which has secured at its free end a supporting-rod 3, extending parallel with the axis of the commutator-cylinder, and upon which is adjustably secured the brush-holder 4. It will be understood that there are devices for rocking the arm 2 and fixing it in any desired position, whereby the position of the brush with relation to the commutator-cylinder may be adjusted in any ordinary and well-known manner. Such mechanism is for this reason not shown. The brush-holder proper consists of a casting 4, formed with a wide slot 5, adapted to receive and guide the collector-brush 6, which latter has the general outline of a flat prismatic plate, with its free end formed to bear at all points upon the surface of the commutator-cylinder, as usual. To one end of the brush-holder is pivoted the frame 7, which supports the mechanism for feeding the brush forward, as it wears off by use. It consists in a bar 8, having on its outer face secured a bracket 9, and this frame when in the position shown in Figs. 1, 2, and 4 closes one end of the slot 5, and in this position a hooked end 10, formed at the free end of bar 8, engages the shank of a screw 11, by which it is locked. There is a square hole formed both in the bracket 9 and in the plate 8, the two holes being in alignment, and through the same passes a square rod 12, provided with a milled head 13, and this rod is screw-threaded, as shown, and has at its end secured a plunger 14, adapted to bear upon the rear end of the brush 6. A helical spring 15 surrounds the rod 12 between the inner face of the outer end of the bracket 9 and an adjusting-nut 16, placed upon the rod 12. A jam-nut 17 may or may not be used. It will be seen that by the mechanism so far de-

scribed the tension of the spring 15 may be adjusted after the brush 6 has been inserted into the slot 5 of the brush-holder 4, with a follower 14 bearing upon the rear end of the brush, while the forward end of the brush bears upon the commutator-cylinder 1.

All these devices for supporting, adjusting, and feeding the collector-brush may be varied in any desired manner, and I do not herein claim the same, and I have only illustrated these devices for the sake of completeness of description.

My present improvement is altogether confined to the construction of the collector-brush, which I will now describe. As shown in the drawings, this brush consists of alternate laminæ of metal 18 and of carbon 19, the carbon being preferably of a fine and uniform grain, while the metal I prefer, without, however, being confined to the same, is copper. I thus assemble alternate layers of copper and carbon and secure the same together by rivets or bolts 20, and by preference the opposite wide faces of the brush are formed of copper. In fact, I may use a single carbon plate having a copper facing-plate 18, applied to both broad faces. The construction, however, shown in the drawings, consisting of two carbon plates with a copper plate between them and a copper plate on the outer face of each carbon plate, I prefer. It will be understood that I may use more than two carbon plates with copper plates between them, together with outer copper facing-plates. A collector-brush thus constructed with alternate layers of carbon and metal has the advantages of carbon and copper brushes combined without the disadvantages of either of them. The good intimate contact produced by the simple carbon brush is also secured by my composite brush, while the freedom from danger of chipping or breaking off which is

secured by the simple copper brush is also secured by my composite brush. It will now be understood that a brush of the kind described may have considerable length between its contact-face and the brush-holder, for there is no danger of breaking, as in the simple carbon brush.

In the drawings I have shown rivets 20 for securing the alternate laminæ of carbon and copper together, and in order to prevent the cracking of the carbon plates by the act of riveting these rivets will preferably be made of some very soft metal, such as lead or tin; but harder rivets may be used without danger of cracking or breaking the carbon if the riveting is done by heating the rivets in place by the passage of a current of electricity through the same and then upsetting the ends by a gentle pressure.

Having now fully described my invention, I claim and desire to secure by Letters Patent—

1. A commutator-brush for dynamo-electric machines, consisting of alternate strips or plates of carbon and metal, substantially as described.

2. A commutator-brush for dynamo-electric machines, consisting of alternate strips or plates of copper and carbon, substantially as described.

3. A commutator-brush for dynamo-electric machines, consisting of a series of alternate strips or plates of carbon and metal, the series terminating at each end with a metal strip or plate, substantially as described.

In testimony whereof I have signed my name to this specification in the presence of two subscribing witnesses.

JAMES F. MC LAUGHLIN.
